UNITED STATES PATENT OFFICE.

ISAAC G. FOSTER, OF PORTLAND, OREGON.

EMERGENCY-AILERON.

1,369,333.

Specification of Letters Patent. Patented Feb. 22, 1921.

Application filed February 25, 1920. Serial No. 361,150.

To all whom it may concern:

Be it hereby known that I, ISAAC G. FOSTER, a citizen of the United States, and a resident of Portland, in the county of Multnomah and State of Oregon, have invented certain new and useful Emergency-Ailerons, of which the following is a specification.

My invention relates more particularly to airplanes and means for righting same when 10 in a nose dive.

The object of my invention is to provide an exceedingly simple and efficient means for bringing an airplane out of a nose dive when it is impossible to do so by the ordinary use 15 of the ailerons and elevators.

I accomplish this result in the manner set forth in the specification following and illustrated in the accompanying drawing, in which:

20 Figure 1 is an end elevation of an airplane shown in dotted lines with the new ailerons in the normal position shown in full lines. Fig. 2 is a plan of Fig. 1 shown in the same manner. Fig. 3 is a perspective view of my 25 device and the means for operating same with the other parts eliminated.

Similar numbers of reference refer to the same or similar parts throughout the several views.

30 The ailerons which I am about to describe form a part of the upper and lower main planes and adjacent to the fuselage, and on the rearward edge of the main planes 4 on each side of the fuselage 5 and forming a 35 part of the main planes 4 are hinged the upper and lower ailerons 6 and 7 by means of the pivots 8. The ailerons 6 and 7 are operably joined by means of the strut 9 which is adapted to transmit similar motion 40 to both of the ailerons 6 and 7. Motion is supplied to the aileron 7 by means of a pend- 45 ent lever 10 rigidly attached to the member 7, which lever is joined by a connecting rod 11 to a second lever 12 mounted on the oper- ating shaft 13 suitably journaled in bear- 50 ings supported by the fuselage 5 and the main plane members 4. An emergency hand lever 14 conveniently placed within reach of the operator is mounted on the shaft 13 and is normally raised against the stop 15 and locked in this position by the sliding latch 16 which may be released by operating the hand grip 17.

It will be observed in Fig. 3 that when the lever 14 is in its locked position that the 55 ailerons 6 and 7 occupy the same relation to the main plane members as would the similar area in the usual form of construction. However, when a pilot discovers his machine in a nose dive from which he is unable to 60 extricate it, he operates the lever 14 which tends to depress the rearward edges of the ailerons 6 and 7 on both sides of the machine, which action assists that of the elevators and rights the machine.

65 I have illustrated my device in a manner which will tend to right the plane by bringing it right side up, which operation, could of course, be reversed if desired by merely permitting the lever 14 to operate in the 70 opposite direction from that which I have shown, without departing from the spirit of my invention.

It will also be observed that I have utilized the stop 15 for limiting the upward 75 movement of the ailerons 6 and 7. This, however, may be accomplished by placing an individual stop on each aileron consisting of a projecting lug on the under side of the aileron, or the upper side of the adjacent 80 main plane at its rearward edge, or in any other manner most convenient for the purpose.

85 While I have thus illustrated and described my invention it is not my desire to limit myself to this precise form or method of application, but intend that it shall cover all forms and modifications that fall fairly within the appended claims.

90 What I claim as new and desire to protect by Letters Patent of the United States is:

1. An airplane righting device consisting of a plurality of ailerons adapted to be operated in a downwardly direction at the same time, a stop means for preventing said ailerons from rising above their normal position, and a locking means for locking said ailerons in any position.

2. In an airplane righting device, the combination of an aileron on the rear edge of 100 each main plane adjacent to the fuselage, each of said ailerons having a hinged union to said main plane in a manner that its rearward end may swing downwardly, a strut member between the upper and lower mem- 105 bers of each pair of ailerons adapted to pro-

vide a uniform motion to both of the members of each pair, a pendent lever attached to the under side of each lower aileron, a connecting rod attached to the lower end of 5 said pendent lever, a rocking arm attached to each connecting link, a shaft member adapted to operate said rocking arms simul-

taneously, a hand lever adapted to actuate said shaft, a stop means arranged to limit the motion of said hand lever in one direction, and a locking device adapted to secure said hand lever in such limited position.

ISAAC G. FOSTER.
